UNITED STATES PATENT OFFICE.

SIGWARTH MANHEIM, OF NEW YORK, N. Y.

SOAP-HANDLE.

1,027,208.

Specification of Letters Patent. Patented May 21, 1912.

Application filed September 7, 1911. Serial No. 648,096.

To all whom it may concern:

Be it known that I, SIGWARTH MANHEIM, a citizen of the United States, and a resident of the city of New York, borough of Manhattan, in the county and State of New York, have invented a new and Improved Soap-Handle, of which the following is a full, clear, and exact description.

My invention relates to soap handles, that 10 is, to devices employed in connection with a bar of soap for enabling the operator to manipulate the latter without placing his hands directly upon it.

My invention comprises a hollow handle 15 made of sheet metal and having, in its entirety, the low specific gravity for enabling it to float when placed in water, and even to float the bar of soap carried by the handle.

My invention further comprehends mechanism carried by the handle for the purpose 20 of enabling it to securely hold the bar of soap.

Reference is to be had to the accompanying drawing forming a part of this specification 25 in which like characters of reference indicate corresponding parts in all the views, and in which—

Figure 1 is a perspective showing my improved soap handle, carrying a bar of soap, 30 and ready for use; Fig. 2 is an inverted plan view of the soap handle complete, the bar of soap, however, being removed; and Fig. 3 is a vertical cross section through the soap handle and bar of soap.

A float 4 has generally a box-like form 35 and is provided with an air compartment 4^a bounded by a top plate 4^b and a bottom plate 4^c. The float is, therefore, a hollow body, and its specific gravity is low enough to float 40 it even when it carries a bar of soap. Secured to the bottom plate 4^c is an anchoring plate 5, and extending from the latter are bosses 6 formed into rows and staggered relatively to each other. The anchoring plate 45 5 is further provided, upon its opposite edges, with teeth 7 and with end projections 8. The purpose of the bosses 6, teeth 7 and end projections 8 is to anchor the bar of soap and hold it securely in position, as 50 hereinafter described. The float 4 is further provided with side extensions 9 and end extensions 9^a which project downwardly beyond the plate 4^c, as will be understood from Fig. 3. The side extensions 9 are provided with slots 10 disposed in pairs, each side extension having one pair. Extending

through the slots 10 and likewise arranged in pairs are blades 11, each provided with an anchor hole 12. The blades 11 are mounted upon leaf springs 13 and for this purpose are provided with sleeves 14 which encircle the springs and grip the same tightly. The leaf springs 13 are bent outwardly at their ends so as to form thumb pieces 15. Secured upon the side extensions 65 9 are sleeves 16 through which the leaf springs 13 extend. When the parts are in their respective normal positions, they appear as indicated by full lines in Fig. 2.

A bar of laundry soap is shown at 17 and 70 is of such size as to fit between the side extensions 9 and the end extensions 9^a.

The operation of my device is as follows: The soap handle is placed over a bar of soap and the thumb pieces 15 are forced outwardly so as to bend the leaf springs 13. The handle is now forced down hard upon the bar of soap so that the teeth 7, bosses 6, and end projections 8 stick into the bar of soap. The leaf springs 13 are now released 80 and the blades 11 are forced into the edges of the bar of soap. By a gentle pressure of the operator's fingers, the leaf springs are forced flatly up against the side extensions 9. The soap is now securely held in position, being anchored, not only by the bosses 6, teeth 7 and end projections 8, but also by the blades 11. As the blades extend in planes parallel with the general plane occupied by the bar of soap, and as the bosses 6 90 and teeth 7 extend in planes crossing the general plane occupied by the bar of soap, it will be noted that the bar of soap is anchored against movement in any direction. 95

I do not limit myself to the precise arrangement of the parts shown, nor to any part used for my invention. Neither do I limit myself to the employment of any particular kind of soap to be used in connection 100 with it.

Having thus described my invention, what I claim as new and desire to secure by Letters Patent is—

1. The combination of a hollow handle 105 provided with side extensions having slots, leaf springs mounted upon said side extensions, and blades mounted upon said leaf springs and extending into said slots for the purpose of penetrating a bar of soap. 110

2. The combination of a floating member provided with a surface for engaging a bar

of soap, leaf springs carried by said floating member, and blades mounted upon said leaf springs, said blades being bent outwardly at their ends and being formed into thumb pieces.

3. As an article of manufacture, a soap handle comprising a hollow handle provided with extending portions having slots therein, leaf springs mounted upon said extending portions and bent outwardly to form thumb pieces, blades carried by said leaf

15 springs and extending through said slots, and an anchoring plate secured to said box-like member and provided with anchors for engaging a bar of soap.

In testimony whereof I have signed my name to this specification in the presence of two subscribing witnesses.

SIGWARTH MANHEIM.
